VENT CAP FOR STORAGE BATTERIES

George F. Couchey, Los Angeles, Calif.

Application June 1, 1949, Serial No. 96,501

1 Claim. (Cl. 136—182)

1

This invention relates to storage batteries and more particularly to vent caps of such batteries.

The primary object of the invention is to provide a vent cap of the character indicated above automatically indicating the supply of water or acid in the storage battery, when applied thereto.

Another object of the invention is to provide a vent cap of the character indicated above permitting refilling of the battery when needed without removing the vent cap.

The invention consists in the details of construction and in the combination and arrangement of the several parts of my improved vent caps of storage batteries whereby certain advantages are attained, as will be hereinafter more fully set forth.

In order that my invention may be better understood, I will now proceed to describe the same with reference to the accompanying drawings, wherein:

Figure 1 is a view in perspective of an embodiment of a vent cap in accordance with the present invention; and

Figure 2 is a view in section in an enlarged scale of the vent cap as shown in Figure 1 illustrated as applied to a storage battery.

The vent cap as embodied herein comprises an elongated hollow body 10 having an open bottom 11 from which a circumferential wall 12 extends upwardly at substantially ninety degrees. The upper portion 13 of the body 10 has a slightly enlarged outside diameter and is provided with an outside thread as at 14 fitting into the tapped hole 15 provided in the top 16 of a standard battery casing B.

On the top end portion of the upper threaded portion 13 of the hollow bottom 11 an outwardly projecting hollow circumferential flange 17 is formed the inside of which communicates with the interior of the hollow body 10. The underside of the hollow flange 17 is disposed flatly on the top surface of the upwardly extending flange 18 surrounding the tapped hole 15 in the top 16 of the battery case B, when the vent cap is applied to a battery case.

In the top wall 19 of the hollow flange 17 an opening 20 is arranged substantially coaxial with the hollow inside of the body 10. An overflow chamber 21 is formed coaxially with and on top of the hollow flange 17 and the top wall 19 of said flange is at the same time the central portion of the bottom wall 22 of the chamber 21, which projects circumferentially beyond the hollow flange 17.

A tapped opening 23 is provided in the wall 24 55 of the overflow chamber 21 and is arranged substantially coaxial with the opening 20 in the top wall 19 of the hollow flange 17. A closure 24 is threaded on its circumference as at 25 and fits threadedly into the tapped opening 23. Centrally of the closure 24 an opening 26 is provided and holes 27 are arranged in said closure equidistantly from the central opening 26 and diametrically opposite to each other.

10 Adjacent to the circumference of the overflow chamber 21 an inlet opening 28 is provided in the top wall 24 of the overflow chamber 21 and is surrounded by a flange 29 extending at right angles to said top wall.

15 A plurality of vents 30 are arranged in the circumferential wall 12 of the body 10 adjacent to the lower edge of the threaded upper portion 13 of said wall.

20 A float body 31 is located inside the hollow body 10 and a stem 32 secured to the float body extends upwardly therefrom and through the opening 20 in the top wall 19 of the hollow flange 17, and the tapped opening 23 in the top wall 24 of the overflow chamber 21. The closure is 25 screwed into the opening 23 and the stem 32 extends slidably through the central hole 26 in said closure. Along the stem 32 of the float 31 markings 33 are arranged at predetermined suitable distances from each other.

30 When the above described vent cap is mounted on a filled storage battery the liquid 34 lifts the float body 31 upwardly sliding the stem 32 so that the level of the liquid 34 in the battery case B can be ascertained by simply looking at the exposed markings 33 on the stem 32. Gas 35 developing in the battery casing enters the body 10 and flows upwardly into the overflow chamber 21, where it cools and condenses into liquid, which returns then through the opening 20 into the body 12. The level of the liquid in said body 40 and in the battery is the same since the bottom 11 of the body 10 is open.

45 When the arrangement of the stem 32 in relation to the closure 24 indicates the need of refilling the battery casing B liquid is poured through the inlet opening 28 until the exposed markings 33 on the stem 32 indicate that the liquid level is at a satisfactory height.

The closure 24 is inserted in or removed from 50 the tapped opening 23 in the top wall 24 of the overflow chamber 21 by inserting a suitable tool (not shown) in the holes 27 and imparting to the closure the required rotary movement.

From the foregoing description it is thought to be obvious that vent caps of storage batteries

2

constructed in accordance with my invention are particularly well adapted for use by reason of the convenience and facility with which they may be assembled and operated.

I claim:

A vent cap for storage batteries comprising an elongated hollow body having an open bottom, the upper portion of the body being exteriorly screw threaded for engagement in a filler opening of a standard battery, a hollow annular flange formed on top of the body, an annular overflow chamber of a greater diameter than that of said flange formed on top of the latter, the interiors of the chamber, the flange and the body inter-communicating with each other by means of co-axially disposed openings, the top wall of the overflow chamber having an opening disposed co-axially with the other openings, a closure removably seated within the opening in said top wall and provided with a central aperture, a float 10
15

within the body, a stem rising from said float and slidably through the aperture in the closure and provided with graduated marks.

GEORGE F. COUCHEY.
